(57) **CLAIM**

We claim the ornamental design for a dishwasher window, as shown and described.

DESCRIPTION

FIG. 1 is a front perspective view of one embodiment of a dishwasher window of the present disclosure;

FIG. 2 is a front elevational view of the dishwasher window of FIG. 1; and,

FIG. 3 is a rear elevational view of the dishwasher window of FIG. 1.

The broken lines shown in the figures are for the purpose of illustrating unclaimed portions of the dishwasher window, and form no part of the claimed design.
